UNITED STATES PATENT OFFICE.

ARTHUR B. CHRISTOPHER, OF ST. LOUIS, MISSOURI, ASSIGNOR TO THE MEASURE-
GRAPH COMPANY, OF ST. LOUIS, MISSOURI, A CORPORATION.

CALCULATOR.

1,343,660.

Specification of Letters Patent. Patented June 15, 1920.

Application filed May 24, 1919. Serial No. 299,579.

To all whom it may concern:

Be it known that I, ARTHUR B. CHRISTOPHER, a citizen of the United States, residing in the city of St. Louis and State of Missouri, have invented new and useful Improvements in Calculators, of which the following is a specification.

This invention relates to a calculator, and particularly to that type of calculator which comprises a plurality of calculating drums which are mounted so that any one of the drums may be presented in the position to be read.

The general object of the invention is to produce a calculator of this type in which the drums are at all times completely enveloped by the case, the parts being so organized, and the case so constructed as to enable the drums to be rotated on their individual axes by means which can be operated from the exterior of the case when the drum which is being used is in the reading position. The different drums carry calculating tables having a different range; or each drum may carry calculating tables for making different kinds of computations. The invention provides for enabling the index number of each drum to be visible in substantially any position a drum may assume. In this way, I produce a very compact calculating device which is particularly useful for making computations upon different rates such as computing the wages of workmen at different rates per hour; or for making any other computations where different rates are used as a multiplier.

The invention consists in the novel features, and in the general combination of parts hereinafter described, all of which contribute to produce a simple and efficient calculator. A preferred embodiment of my invention will be particularly described in the following specification, while the broad scope of my invention will be pointed out in the appended claims.

In the drawing, which fully illustrates a preferred embodiment of my invention,

Figure 1 is a plan of the calculator;

Fig. 2 is a side elevation;

Fig. 3 is an end elevation;

Fig. 4 is a vertical cross-section taken at one end of the machine, certain parts being broken away;

Fig. 5 is a perspective of one of the computing strips such as carried by the drums;

Fig. 6 is a side elevation, broken away, of a holder which may be employed for removably holding the computing strips on the drums;

Fig. 7 is an end elevation of the strip- 60 holder shown in Fig. 6;

Fig. 8 is a longitudinal vertical section through the device; and

Fig. 9 is a fragmentary perspective of one end of the case of the machine. 65

In practising my invention, I provide a plurality of individually rotatable calculating drums which are disposed circumferentially about a central axis; these drums carry calculating tables on their faces. I also provide a case which completely envelops the drums in any position they may assume, and this case is provided with a sight-opening at the point where the drums are positioned in order to be read, that is to say, at the point 75 where the tables on the drums are visible through the sight-opening. Associated with each drum, I provide means for rotating it on its individual axis so as to bring the different tables on the drum into alignment with 80 the sight-opening; the case is so constructed as to render this rotating means accessible from the exterior of the case when its corresponding drum is in its reading position.

In order to accomplish these results, I 85 provide a plurality of calculating drums 1 which are arranged parallel to each other, and with their axes disposed circumferentially about a central horizontal axis. I provide means for supporting and for rotat- 90 ing these drums around the central axis, comprising a central shaft 2 near the ends of which, disks or heads 3 are rigidly attached to bushings 4 carried rigidly on the shaft. On the faces of the drums, I provide 95 a plurality of longitudinally extending computing strips 5, one of which is illustrated in Fig. 5. These strips may be formed of celluloid or paper, and are provided with divisions progressively numbered, for example, 20, 30, 40, 50, etc. 100

In order to hold these strips conveniently on the faces of the drums, I provide a holder corresponding to each strip, which is simply in the form of a strip of metal extending 105 longitudinally on the faces of the drum having upwardly and inwardly bent flanges 7, the strips being inserted in the holders by shoving them longitudinally into the holders from one end. As illustrated in Figs. 110

6 and 7, the body 8 of the holder is represented as flat, but it should be understood that this metal is very light, and the body 8 of each strip will assume the convex form 5 of the drum when attached to the drum as illustrated in Fig. 4.

I provide means associated with each drum for rotating it upon its individual axis, consisting of a pin 9 fixed in the end of 10 the drum and operating as a pivot passing through one of the heads or disks 3, the outer end of each of these pins being provided with a thumb-head 10. I provide each drum with a plurality of the computing strips 5, for example six strips. This will give considerable range for the instrument. Evidently by rotating the thumb-head 10, its corresponding drum may be rotated so as to bring any strip into the desired position. 20 The ends of the drums opposite to the pins 9 are rotatably supported in the opposite head 3 on central pins 11.

Any suitable means may be provided for holding the drums in any position in which 25 they are left. For this purpose, I may provide each pin 9 with a rigidly attached star-wheel 12, with which coöperates a resilient detent 13, secured on the inner face of the adjacent head 3, see Figs. 4 and 8. This 30 star-wheel 12 has as many notches as there are strips on the drum. When the drum is stationary on its axis, the detent 13 occupies one of these notches and holds the drum against accidental rotation.

35 The drums are completely enveloped in any position they may assume, by a case 14 which may be formed of light sheet metal, presenting a cylindrical upper portion or dome 14^a, said case seating upon and being 40 attached to a base-plate or board 15. The rear end wall 16 of this case may be formed of wood provided with a bushing 17 for rotatably supporting the outer end of the central shaft 2.

45 In order to enable the thumb-heads 10 to be accessible from the exterior of the case to enable any drum to be rotated when it is at the reading position, I provide the end wall of the case with a slot. This slot is 50 preferably of arcuate form and the thumb-heads 10 simply project through the slot, see Fig. 8.

In the present instance, I construct the end wall 18 with an inwardly offset upper portion 19, and an outwardly offset lower portion 20, said portions 19 and 20 being integrally connected by a horizontal extension 21. In other words, I simply form the end wall 18 of a vertical plate pressed so as 60 to present a jog or horizontal offset. In the lower portion 20 of the end wall 18, the shaft 2 is rotatably mounted, passing through a suitable bushing 22, and on the exterior of the case, this shaft is provided 65 with a suitable knob 23 for rotating the

shaft 2, thereby enabling the operator of the instrument to bring any drum to the reading position.

In order to enable the thumb-heads to pass up from the lower portion of the case, 70 the horizontal extension 21 is formed with a notch or slot 25 which connects with the slot 24, see Fig. 9.

I provide the end faces 26 of the thumb-heads, with index numbers indicating the 75 range of the tables corresponding to that drum, see Fig. 3, and in order to enable these index numbers to be visible in substantially all positions the drums may assume, I provide the lower portion 20 of the end 80 wall 18 with an arcuate slot 27.

The reading position, that is to say, the point at which the tables of the drums are visible, is preferably located directly over the shaft 2, at the highest point on the dome 85 14^a, and at this point, I provide a sight-opening 28 which may be covered by a glass strip or window 29. Adjacent this point, the case is formed with undercut slots 30 which receive two scales 31 and 32, the scale 90 31 having divisions progressively numbered to represent units of any kind, for example, hours. The opposite scale 32 may be provided with progressively numbered divisions corresponding to half hours. 95

The case is also formed so as to present a longitudinally extending guideway 33 carrying a movable slide or runner 34. This slide 34 is simply a bar having a slot 35 which extends transversely across the sight-opening 28 and the two scales 31 and 32. In Fig. 1, the computing scale which is in the reading position, that is to say, under the window 29, represents a rate of 20¢ per hour. The numbers on this scale aline with the 105 numbers on the scales 31 and 32 and are functions of the unit rate and the numbers on these scales, for example, the figure on the computing scale opposite the third hour is "60," indicating that at the rate of 20¢ 110 per hour the total for the three hours will be 60¢. To prevent errors, the slide or runner 34 should be moved to the point on the scale where the reading is to be taken, for example, in Fig. 1, the slide is placed at the 115 fourteenth hour, and the computing scale indicates "280," that is to say, \$2.80 which should be the total for this rate.

It should be understood that the scale shown in Fig. 1 is so simple, that the computation could easily be made mentally, but in actual practice, the rate might include a fractional number, so that the computations might not always be so simple.

In order to hold any given drum in position at the reading point any suitable detent device may be employed, for example, this detent device may be similar to that described for detaining the drums against rotation on their individual axes, that is to 130

say, I provide the shaft 2 near one end with a rigid star-wheel 36 having a number of notches 37 corresponding to the number of drums carried in the instrument, and co-
5 operating with the notches, I provide a detent 38 which is pressed by a coil spring 39 so as to hold the detent in engagement with the star-wheel. This will give the shaft 2 a step-by-step movement when it is rotated.
10 In the mode of operation of the machine, the operator examines the index numbers on the end faces of the thumb-heads to ascertain the present position of the drum which he desires to employ in the computation
15 about to be made. He then seizes the knob 23 and rotates the shaft 2 so as to carry the desired drum up to the reading position. After the drum arrives at the reading position its thumb-head 10 is then rotated
20 until the desired scale of that drum is presented under the sight-opening. The slot 34 is then slid to the proper point and the reading taken off of the drum.

It is understood that the embodiment of
25 the invention described hereinabove, is only one of the many embodiments the invention may take, and I do not wish to be limited in the practice of my invention nor in my claims, to the particular embodiment set forth.

What I claim and desire to secure by Letters Patent is:

1. In a calculator, the combination of a plurality of individually rotatable calculating drums disposed circumferentially about a central axis, said drums having calculating tables on their faces, a case having a sight-opening, means for supporting and for rotating said drums about said central axis
35 to bring any of the drums into position opposite said sight-opening, said case enveloping all of said drums in any position the drums may assume, and means associated with each drum for rotating the same upon
40 its individual axis, said last named means lying outside of the case when the drum carried thereby lies opposite said sight-opening.

2. In a calculator, the combination of a plurality of individually rotatable calculating drums disposed circumferentially about a central axis, said drums having calculating tables on their faces, a case having a sight-opening, means for supporting and for rotating said drums about said central axis to bring any of the drums into position opposite said sight-opening, said case enveloping all of said drums in any position the drums may assume, a member associated with each drum for rotating the same upon its individual axis, the wall of said case having an opening through which said last named member projects when its corresponding drum lies opposite said sight-
55 opening.

3. In a calculator, the combination of a plurality of individually rotatable calculating drums disposed circumferentially about a central axis, said drums having calculating tables on their faces, a case having a sight-opening, means for supporting and for rotating said drums about said central axis to bring any of the drums into position opposite said sight-opening, said case enveloping all of said drums in any position the drums may assume, a thumb-head associated with each drum for rotating the same upon its individual axis, said case having an end wall with an inwardly offset upper portion having a slot therein along
70 which each thumb-head passes, and through which each thumb-head projects when its corresponding drum lies opposite said sight-opening.

4. In a calculator, the combination of a plurality of individually rotatable calculating drums disposed circumferentially about a central axis, said drums having calculating tables on their faces, a case having a sight-opening, means for supporting and for rotating said drums about said central axis to bring any of the drums into position opposite said sight-opening, said case enveloping all of said drums in any position the drums may assume, a member carried
75 by each drum for rotating the same upon its individual axis, said case having an end wall with an inwardly offset upper portion having a slot therein through which said last named member projects when its corresponding drum lies opposite said sight-opening, said end wall having an outwardly offset portion with an opening therethrough, through which the ends of said members are visible, the ends of said members bearing
80 numbers indicating the range of the calculating tables carried by the corresponding drum.

5. In a calculator, the combination of a plurality of individually rotatable calculating drums disposed circumferentially about a central axis, said drums having calculating tables on their faces, a case having a sight-opening, means for supporting and for rotating said drums about said central axis to bring any of the drums into position opposite said sight-opening, said case enveloping all of said drums in any position the drums may assume, a thumb-head associated with each drum for rotating the same upon its individual axis, said case having an end wall with a slot therethrough, along which each thumb-head passes, and through which each thumb-head projects when its corresponding drum lies opposite said sight-
105 opening.

6. In a calculator, the combination of a plurality of individually rotatable calculating drums disposed circumferentially about a central axis, said drums having calculating

ing tables on their faces, a case having a sight-opening, means for supporting and for rotating said drums about said central axis to bring any of the drums into position opposite said sight-opening, said case enveloping all of said drums in any position the drums may assume, a thumb-head carried by each drum for rotating the same upon its individual axis, said case having an end wall with an inwardly offset upper portion having a slot therein and having an

outwardly offset lower portion, said offset portions being connected by a substantially horizontal extension of said wall, said horizontal extension having a slot communicating with said first named slot through which the said thumb-head of each drum passes when the drum moves toward said sight-opening. 15

In testimony whereof I have hereunto set 20 my hand.

ARTHUR B. CHRISTOPHER.
